UNITED STATES PATENT OFFICE.

CHARLES A. ERNST, OF LANSDOWNE, PENNSYLVANIA, ASSIGNOR TO SILAS W. PETTIT, OF PHILADELPHIA, PENNSYLVANIA.

PROCESS OF PRODUCING AND FORMING TWISTED FILAMENTS FROM VISCOSE OR SIMILAR MATERIAL.

No. 876,533.

Specification of Letters Patent.

Patented Jan. 14, 1908.

Application filed January 17, 1906. Serial No. 296,492.

To all whom it may concern:

Be it known that I, CHARLES A. ERNST, a citizen of the United States, and a resident of Lansdowne, State of Pennsylvania, have 5 invented certain new and useful Improvements in the Process of Producing and Forming Twisted Filaments from Viscose or Similar Material, of which the following is a full, clear, and exact description.

10 In forming threads of what is known as artificial silk or similar material, it is common to eject the viscose or other similar viscous substances into a fixing or coagulating solution through a spinneret provided 15 with a plurality of small apertures, the spinneret being given at the same time a rotary motion, whereby the filaments are wrapped or twisted about each other as they traverse the coagulating bath. The thread so 20 formed is then subjected to any further chemical treatment and is washed and dried in any suitable manner. The twisting together of the filaments in the coagulating bath is undesirable, however, since in addition 25 to being easily broken by such twisting, the newly formed filaments are often not completely or thoroughly acted upon by the fixing solution and the tendency of the filaments is to mat or stick to each other, which 30 greatly diminishes the quality and the appearance of the finished thread.

The object of my invention is to treat the thread both in the bath and in the latter steps of the process in an untwisted condition such as is disclosed in my United States Patent, No. 808,148, of December 26, 1905, and to postpone the step of spinning or twisting the filaments together until the end 35 of the process of forming the same, whereby 40 each individual filament will be more thoroughly acted upon by the chemicals and by the baths in which the filaments are washed, whereby a stronger and better product is obtained.

45 A further object of my invention is to so wind the thread as it emerges from the coagulating bath upon the spools on which it is treated in the various succeeding steps of the process and from which it is unwound 50 and conducted to the twisting machine, that a broken filament may be easily detected.

A further object of my invention is to so spin the thread that a broken filament will not accumulate on the spool from which it

is being unwound, but will, in the majority 55 of cases, be caught and carried along and spun together with the unbroken filaments without necessitating the stopping of the spinning machine or any manipulation on the part of the operator. 60

In the drawings forming a part of this specification, Figure 1 indicates a spool, drum or ring upon which the untwisted thread of artificial silk is wound as it emerges 65 from the fixing bath, upon which it is subjected to any further chemical action, such as a further fixing, a bleaching, or a washing of the same, and from which it is conducted to the twisting machine; Fig. 2 shows my improved process of twisting together un- 70 twisted filaments.

The steps employed by me in the manufacture of what is commonly known as artificial silk are as follows:—The viscose or similar material is forced in a plurality of 75 strands or filaments from a cap or plate perforated with a number of very small openings into a coagulating or fixing bath and the several filaments so formed are collected into a single untwisted thread which is conducted 80 to a rotating spool or cylinder upon which it is wound by means of any suitable traverse mechanism. The filaments so wound are then subjected, while on the spool, to the various succeeding steps of the process and are 85 then washed and dried on the spool. By means of these steps the filaments are thoroughly changed into a strong brilliant thread of artificial silk. The untwisted thread is then unwound and conducted directly to a 90 twisting machine of any suitable description, whereby the filaments are bound together and a finished twisted thread is produced.

In attempting to conduct an untwisted thread from the spool or bobbin upon which 95 it is wound directly to the twisting machine, I have found that when one of the filaments forming the thread is broken, it will not ordinarily be conducted away from the spool upon which it is wound together with the 100 other filaments of the thread, but the broken filament will remain on the spool and as the thread is further unwound will accumulate in loosely wound courses or ridges and will finally break the thread being twisted. 105

With the thread wound on the spool in close courses it is almost impossible to distinguish and separate a broken or loose fila-

ment from the rest of the thread remaining on the spool, and consequently when one of these filaments is broken it becomes almost necessary to cut off and throw away all the 5 untwisted thread remaining on the spool. My invention has special reference, therefore, to the winding of the untwisted thread upon the bobbin from which it is delivered to the twisting machine, and also to the step of 10 twisting itself and the drawings illustrate these two portions of my invention.

Referring to the drawings, 1 indicates a spool of any suitable construction upon which the untwisted thread is laid in such a 15 manner that the individual turns or convolutions of the thread will cross those of the preceding course at a fairly sharp angle. The spool when wound, will present a net or open mesh appearance as plainly indicated in Fig. 20 1. This open mesh winding may be accomplished by a variety of known winding mechanisms in which the traverse rod by which the thread is laid on the spool is given a comparatively rapid movement or reciprocation. 25 2. In other words, the spool is rotated but a few times, while the traverse rod is given a single reciprocation. This results in each convolution or turn of a course of the thread on the spool being laid at a considerable distance 30 from the preceding turn or convolution in the same course. In Fig. 1, the distance between the different convolutions is indicated by the numeral 2. The spool 1 is positively driven in any suitable manner to deliver the thread 35 through the guide eye 3 in the thread-board 4 to the thread guide 5 in the flier 6, which is secured to and is positively rotated by the spindle 7. The spindle 7 is rotated through the whirl 8, belt 9, and tin roller 10 of the 40 twisting machine.

11 indicates the traverse or builder form which is reciprocated vertically in any direction parallel to the spindle by any suitable builder mechanism, (not shown) by which a 45 reciprocatory motion is communicated to the bobbin 12 loosely mounted on both said traverse form and said spindle. The thread passing through the thread guide 5 is wound upon the bobbin 12 as fast as the same is delivered from the bobbin 1 as is usual in twisting 50 machines.

I so locate the spool 1 with respect to the thread-board 4 and I make the thread guide 3 of so large a size that the twist imparted to 55 the thread by the flier 6 will not terminate at said thread-board, but will extend from the thread guide 5 at the end of the flier up through said guide eye 3 to the surface of the spool from which the thread is being delivered. The result of this construction is that 60 should one of the filaments become broken during any of the steps of the process as indicated above, the filaments which are not broken will, in the majority of cases, catch 65 and twist in that broken filament rather than

allow the same to accumulate on the spool. If, however, such filament be not caught, its accumulation on the spool will be in substantially concentric parallel courses and can be readily distinguished from the untwisted threads which are laid at a considerable angle to a plane normal to the axis of the spool. 70

While I have described a construction in which the ring or spool is positively driven and in which the bobbin is dragged around the spindle by the thread being twisted, my invention contemplates the employment of any suitable twisting mechanism in which the twisting extends back the whole length of the thread up to the point of its delivery 80 from the surface of the bobbin or spool from which it is being unwound, and in which the twisting together of the unbroken filaments at the surface of the spool will nip or bind in and carry along any loose end or filament 85 that may have been broken during the process of twisting.

Having thus described my invention, what I claim and desire to protect by Letters Patent of the United States, is:— 90

1. The process of forming a twisted thread of artificial silk, which consists in winding upon a spool a thread consisting of a plurality of untwisted filaments, conducting said thread from said spool to a suitable spinning head, and simultaneously twisting the same for the entire distance between the spinning head and the point of the delivery of the thread from the spool. 95

2. The method of forming a twisted thread 100 of artificial silk, or similar material, which consists in forming a thread composed of untwisted parallel continuous filaments, winding said untwisted filaments in open courses upon spools, and then unwinding 105 said untwisted thread, and simultaneously twisting the same from the point where it leaves the spool, to catch any loose end or broken filament and bind it in with the unbroken filaments while they are being 110 twisted together.

3. The process of forming a twisted thread of artificial silk, which consists in winding in separated convolutions upon a spool a thread 115 consisting of a plurality of untwisted filaments, conducting said thread from said spool to a suitable twisting head, and twisting said thread the entire distance between said twisting head and the point where it leaves the spool. 120

4. The process of twisting a thread composed of a plurality of untwisted filaments, which consists in unwinding said thread from a spool upon which it is wound in separated convolutions, twisting said thread 125 for the entire distance between said head and the point where the thread leaves the spool, whereby any loose or broken filaments will be caught by the unbroken filaments being twisted as they leave the spool, and the 130

twisting of all the filaments will be continued without any interruption of the twisting operation.

5. The method of twisting filaments into a twisted thread, which consists in winding a thread composed of substantially parallel and untwisted filaments upon a spool, with each convolution of a course separated by a considerable distance from the other convolutions in the same course, delivering said thread from said spool directly to a suitable twisting machine and twisting the same for the entire distance between the twisting mechanism and the surface of the spool, 10 whereby any loose or broken filament is caught at its point of delivery from said spool by the unbroken filaments as they are twisted at said point.

6. In the twisting of a thread composed of 20 substantially parallel untwisted filaments, the method of preventing the separation of a

broken filament from the rest of the filaments forming the thread, which consists in conducting the untwisted thread from the spool directly to a twisting mechanism and twisting the thread the entire distance between the twisting mechanism and the surface of the spool. 25

7. In the twisting of a thread composed of long untwisted filaments wound upon a spool, the method of catching and binding in a broken end, which consists in twisting together the unbroken filaments at the point where the same leave the surface on which they are wound and from which they are 30 being delivered.

In witness whereof I hereunto set my hand this 13th day of January, A. D. 1906.

CHARLES A. ERNST.
